UNITED STATES PATENT OFFICE.

ADELBERT G. FOLSOM, OF CHICAGO, ILLINOIS.

DESIGN FOR A COMBINED CIGARETTE CONTAINER AND ASH TRAY.

Application filed October 5, 1922. Serial No. 3,889. Term of patent 3½ years.

To all whom it may concern:

Be it known that I, ADELBERT G. FOLSOM, a citizen of the United States, residing at Chicago, in the county of Cook and State of Illinois, have invented a new, original, and ornamental Design for Combined Cigarette Container and Ash Tray, of which the following is a specification, reference being had to the accompanying drawing, forming part thereof.

bined cigarette container and ash tray, showing my new design,

Figure 2 is a side elevation of my combined cigarette container and ash tray, and

I claim:

The ornamental design for a combined cigarette container and ash tray, as shown.

ADELBERT G. FOLSOM.
